UNITED STATES PATENT OFFICE.

GEORGE JOHN ALTHAM, OF FALL RIVER, MASSACHUSETTS, ASSIGNOR TO AERO AND MARINE MOTOR COMPANY, OF BOSTON, MASSACHUSETTS, A CORPORATION OF MASSACHUSETTS.

INTERNAL-COMBUSTION ENGINE.

No. 874,920.

Specification of Letters Patent.

Patented Dec. 31, 1907.

Application filed February 2, 1907. Serial No. 355,525.

To all whom it may concern:

Be it known that I, GEORGE JOHN ALTHAM, a citizen of the United States, residing at Fall River, in the county of Bristol 5 and Commonwealth of Massachusetts, have invented certain new and useful Improvements in Internal-Combustion Engines, of which the following is a specification.

This invention relates to internal combustion engines, and particularly to the admission of a charge to and the expulsion of the remaining products of combustion from such an engine of the two cycle type.

The displacement of an exploded charge 15 by a fresh charge may be more or less complete and as it is on the completeness of this act that much depends, it is the object of the present invention to provide means for securing satisfactory displacement of the exploded charge and even distribution of the 20 fresh charge within the cylinder.

To this end I have devised a certain novel deflector and mounted and arranged the same with reference to the ports whereby 25 the parts combine to secure the results above stated as desired. The structure and mode of operation will be more fully disclosed in the specification which follows and is shown in the accompanying drawings which form 30 a part thereof, in which drawings

Figure 1, is a section of engine showing my invention in vertical section. Fig. 2, is a section of engine showing the deflector in rear elevation, and Fig. 3, is a cross-section 35 showing the deflector and arrangement of parts in plan.

A is an engine cylinder having a piston B working therein.

C is a crank, D a casing therefor and E a 40 connecting link between said crank and piston.

G is an intake port uncovered by the piston B, and F is a by-pass through which the compressed charge is transmitted from the 45 port b in the piston B.

H is an exhaust port arranged opposite to G. The ports G and H are cut in the curved

wall of the cylinder and are therefore curved or radial ports and as they are oppositely disposed the ends of said ports are nearer together than their central portions. 50

I is a deflector mounted on the upper face of the piston in front of port F. The deflector is bent slightly on the same general curve of the port F, but has its ends i¹ refused for a short distance. The upper edge 55 of the deflector I is sloped downward toward the center so that the ends i¹ are higher than the central portion i.

Referring to Figs. 2 and 3 it will be seen 60 that the charge entering the cylinder through the port F are deflected upward and laterally. At the center, however, when the distance between ports is greatest, the charge is least deflected, while at the ends of the deflector, where the curving ports approach nearest, the deflection is greatest. In order 65 to prevent the charge from rushing around the ends of the deflector, I have provided the refused portions i¹ which partially baffle the spread of the gas in this direction and assist in its uniform spread throughout the cylinder. 70

It is obvious that the invention disclosed 75 may be varied by change of form without departing from the spirit of my invention.

What I therefore claim as my invention and desire to secure by Letters Patent, is:

1. A deflector for an explosion-engine having a greater height at its ends than at its 80 center.

2. In a device of the class described, a radial port and a deflector therefor having a greater height at its ends than at its center.

3. In a device of the class described, a 85 pair of oppositely disposed radial ports and a deflector therebetween having a greater height at its ends than at its center.

In testimony whereof, I affix my signature in presence of two witnesses.

GEORGE JOHN ALTHAM.
